[57] CLAIM

The ornamental design for a panel structure for a portable panel saw, as shown and described in the accompanying figures.

DESCRIPTION

FIG. 1 is a left-side perspective view of a panel structure for a portable panel saw showing our new design;

FIG. 2 is a right-side perspective view of the panel structure for a portable panel saw of FIG. 1; and,

FIG. 3 is a front view of the panel structure for a portable panel saw of FIG. 1.

The broken line showing is for illustrative purposes only and forms no part of the claimed design.

CLAIM

We claim the ornamental design of a paint brush, as shown and described.

DESCRIPTION

FIG. 1 is a perspective view of a paint brush of the present invention;
 FIG. 2 is a left side elevational view thereof, the right side elevational view being identical thereto;
 FIG. 3 is a top plan view thereof;
 FIG. 4 is a bottom plan view thereof;
 FIG. 5 is a rear elevational view thereof; and,
 FIG. 6 is a front elevational view thereof.
 The ornamental design which is claimed is shown in solid lines in the drawings. The broken lines in the drawings are for illustrative purposes only and form no part of the claimed design.
